F. ZOLL,
CORE MAKING MACHINE,
APPLICATION FILED MAR. 18, 1921.

1,427,427.

Patented Aug. 29, 1922.

UNITED STATES PATENT OFFICE.

FRED ZOLL, OF BIRMINGHAM, ALABAMA.

CORE-MAKING MACHINE.

1,427,427.

Specification of Letters Patent. Patented Aug. 29, 1922.

Application filed March 18, 1921. Serial No. 453,206.

To all whom it may concern:

Be it known that I, FRED ZOLL, a citizen of the United States, and a resident of the city of Birmingham, in the county of Jefferson and State of Alabama, have invented certain new and useful Improvements in Core-Making Machines, of which the following is a full, clear, and exact description, reference being had to the accompanying drawings, forming part of this specification.

My invention relates to machines for the manufacture of dry sand cores and more particularly to power-operated machines for this purpose.

In the development of machines of this type, the ease of insertion of the sand, simplicity of operation in forming the core and ease of removal of the core are the essentials, together with a simple method of changing the length of stroke of the movable die portion of the core and of changing the die itself for different cores.

So far as I have been able to ascertain, there has been no other machine for making a core of straight simple section such as those used as center cores in making cast iron car wheels (or any cylindrical, square or other straight shape) manufactured, using the same methods that I have used, as other machines for making this kind of core have been made upon the principle of forcing sand through a die the same shape as the desired core, which method is comparatively inaccurate and does not permit the use of any beveled ends, tapered vents, and the like, as with that type of machine the vent is a continuous hole through the sand, and the core is sawed off in lengths as desired. According to my invention the sand is placed in a mold and compressed to the desired conformation by moving the base of the mold.

The provision of a mechanism well adapted for use on all of the above points is the object of my invention, and I accomplish said object by the certain construction and arrangement of parts to be hereinafter more specifically pointed out and claimed.

In the drawings,

Figure 1 is a front elevation of the machine.

Figure 2 is a top plan view showing the core box open.

Figure 3 is a detail section on the line 3-3 of Figure 1.

As shown, the device has a frame 1 of tubular nature, with feet 2, and an air inlet

pipe 3. No air valve is shown, as this will ordinarily be in the air pipe at some convenient point to the operator of the machine.

The lower portion of the casing serves as 60 a cylinder, as at 4, for a piston 5. The cylinder is provided with air outlets 6 above the upward limit of the path of the piston, and it has also a head 4^a through which the piston rod passes.

The piston rod 7 carries a cross head 8, suitably guided over a pair of rods 9, 9, that are set inside of the casing at an open portion 10 thereof.

The rods 9 have collars 11 thereon, said 70 collars having set screws 12 for positioning them at the desired fixed point along the rods, thereby limiting the upward and downward strokes of the cross head and piston. The piston rod, as shown, is secured to the 75 cross head by passing through the same centrally and being held in adjusted position by nuts 13.

The cross head also has an arm 14 extending out through the casing where it is 80 mounted on a slide rod 15, that reciprocates in a socket piece 16 in the top 17 of the frame. The rod acts as an indicator to show the operator the upper and lower limit of the stroke of the piston.

Set into the center of the top of the casing is a cylindrical piece 18 having a flange 19, which is countersunk into the said top. At what may be termed the rear of this flange is a pivot post 20, which carries the two 90 half cylindrical portions 21 and 22 of the core box hinged thereto below, while the upper portions of the two half cylinders are provided with ears in alignment with the pivot post for hinging the half cylinders 95 together at the upper end. The top 17 is slotted at 23 and the cylinder 18 has lugs 18^a to slide down through the slots. The lugs will then be turned by revolving the cylinder to bring them up against stop pins 100 23^a, depending from the top, thus securely fastening down the cylinder and flange.

One of the halves of the core box is provided with a pivot bolt 24 for a cover 25, which said cover has a notched portion 26^a 105 to engage over a bolt 26 on the other half of the box. This second half has a latch 27 thereon to engage down over an ear 28 on the half carrying the lid.

Thus when the box is closed and the cover 110 swung over the assembly and the latch thrown, the two halves of the core box will

be securely held together and will form a continuation, interiorly, of the diameter of the cylinder 18.

The end of the piston rod is equipped 5 with a detachable cap 29, which is of smaller diameter than the cylinder 18 and the core box. This cap is adapted for acting as a seat for an annular plate 30, having a flange 31 to engage down over the head.

10 The cap has a threaded hole 31^a in the upper end thereof, into which is screwed the vent plunger 32 for the core to be made.

The annular plate and particularly the vent plunger are to be changed dependent 15 upon the special core that it is desired to make. The plate is of the diameter of the core box that is in use, and of the cylinder 18 that is in use. The head or cap 29 is also adapted for change dependent upon the 20 piece of work to be done and the size of the cylinder 18 to be used therewith.

The machine operates as follows: First selecting the desired vent plunger and arranging the cylinder 18, core box and annular plate for the special work to be done, the 25 operator adjusts the collars that control the length of stroke of the piston. He then lowers the piston to the bottom of its stroke, and closes the core box, leaving the top 30 open. Into this open top he places the sand, having latched the halves of the box, and swings the lid into place. An opening of the air valve will then cause the piston rod to rise and will force the annular plate and 35 vent plunger up into the sand, to form the core.

After the core is formed, the box is opened and the core removed, after which the piston is again depressed and the work con- 40 tinued.

I have not shown the air valve, but it will be understood that this may be a foot treadle operated valve, having a position of compressed air inlet into the cylinder and a 45 position of escape for the air from the cylinder into the atmosphere. In compound machines worked out on the principle above described, the piston operation may well be both upward and downward, by utilizing 50 any well known form of compressed air

engine and the number of units may be increased within limits of the number convenient to single operators.

I have not shown or described any such forms, as it is my desire in this application 55 to show and describe a simple form of core molding machine, which is positive in its operation and easy to fill with sand and to remove the completed core, as well as easy to change so as to make different forms of 60 core.

Having thus described my invention, what I claim as new and desire to secure by Letters Patent, is:—

1. In a machine for making cores, the 65 combination with a driven piston, of a cylindrical element, and a reciprocating element therein, comprising in part a vent plunger or the like, driven by said piston, a closable filling opening in the cylinder element for 70 sand, and means for opening the cylinder element laterally for removal of completed cores, said machine having means for adjustably limiting the stroke of the piston.

2. In a machine for making cores, the 75 combination with a driven piston, of a cylindrical element, and a reciprocating element therein, comprising in part a vent plunger or the like, driven by said piston, a closable filling opening in the cylinder element for 80 sand, and means for opening the cylinder element laterally for removal of complete cores, said machine having a visible indicator to show the length of movement of the reciprocating element. 85

3. In a machine for making cores, the combination with a driven piston, of a core box formed to open laterally for removal of work, means for positioning the core box removably on the machine, a rod on the piston 90 reciprocating in the core box and a detachable element on the rod adapted to serve as a piston in the core box, said element comprising in part a vent plunger or the like, said core box having an opening at the top 95 for filling and a lid element, adapted to be secured fast over said opening, during operation of the machine.

FRED ZOLL.
